TWO-HAND CONTROL FOR POWER
ACTUATED MACHINES

Ernest Davis, Syracuse, N. Y., assignor to The
Prosperity Company, Inc., Syracuse, N. Y., a
corporation of New York

Application June 6, 1941, Serial No. 396,959

5 Claims. (Cl. 121—38)

This invention relates to two hand controls for power actuated machines having an operating movement, which is dangerous to the operator, as a machine having an opening and closing movement; and has for its object a two hand control including a pressure tank, a pair of manually operable control valves, either one of which is of insufficient size or capacity to conduct sufficient pressure or working fluid from the tank to effect the operation of the machine, so that the instantaneous or simultaneous operation of both manual valves is required to effect the operation, and means in the control valve system for supplying sufficient pressure through the control valve when both are simultaneously operated to effect the operation of the machine, and also a disabling or bleeding means which reduces the pressure in the tank when only one manual valve is operated to below the required pressure for operating the machine when the other manual control is operated, so that if the valves are alternately operated and not simultaneously operated, there is not sufficient pressure in the control system to effect the operation of the machine.

It further has for its object an arrangement of the bleeder or disabling means in such a manner that the pressure is maintained to operate the machine only long enough to permit the machine to operate if the operator holds both manual controls in operated position, after the machine closes, or in machines as punch presses, in which each operation, the opening movement immediately follows the closing movement, repeated operations can not take place upon one operation of the two manuals.

It further has for its object a master control valve and locking means therefor.

Other objects appear throughout the specification.

The invention is illustrated as applied to a garment and laundry press in which a press head moves inwardly and out of coaction with a press table or buck.

The invention consists in the novel features and in the combinations and constructions hereinafter set forth and claimed.

In describing this invention, reference is had to the accompanying drawings in which like characters designate corresponding parts in all the views.

Figure 1 is a perspective view of a laundry press embodying this invention.

Figure 2 is an enlarged sectional view of the master control valve.

Figure 3 is a section on line 3—3, Figure 2.

Figure 4 is a diagrammatic view, partly in section, illustrating the control system and power system for the cylinder and piston motor

of the press, the various valves and the cylinder and piston motor being shown in longitudinal section.

Figures 5 and 6 are respectively a side elevation and an end view of a modified form of the master control valve.

Figure 7 is an elevation, partly in section, of a second modified form of the control valve.

Figure 8 is a diagrammatic view similar to Figure 4 of a modified form of the control system.

Figure 9 is a perspective view of a modified form of the manuals for operating the manually operable valve and the arrangement of manuals on the table of the pressing machine.

The pressing machine to which this control system is applied, as here shown, comprises a head 1 movable toward and from a buck 2 suitably mounted on a frame 3 of the machine above the table 4. The head 1 is carried by a head carrying lever 5 pivoted at 6 to an arm 7 rising from the frame 3 in the rear of the buck 2. It is actuated by a cylinder and piston motor including a cylinder 8 suitably pivoted within the frame to have an oscillating movement, and a single acting piston 10 in the cylinder, the rod 11 of which is connected at 12 to a lever 13 forming part of a motion transmitting means between the piston rod and the head carrying lever 5. In so far as this invention is concerned, the construction of the machine forms no part of this invention, as the invention relates to two hand control for controlling the flow of a working or pressure fluid to the cylinder 8.

The two hand control includes a self-closing, normally-closed master valve for controlling the flow of working fluid from a main pressure line to the motor, a pair of self-closing, normally-closed manually operable control valves connected to pressure operated means, which open the master valve, each manual control being of insufficient size or capacity to conduct sufficient pressure fluid to operate the pressure operated means in the master control valve, each manual control valve being a combined intake and exhaust with the intake normally closed and the exhaust open, a pressure tank also connected in the main line and to the manually operated control valves and being of sufficient capacity only to supply pressure fluid through the manually operated control valves to the pressure operated means of the master valve for one opening operation only of the master control valve, upon simultaneous or instantaneous operation of both controls, together with disabling means for releasing the pressure fluid to the pressure operated means of the master valve at a predetermined rate when either or both control valves are operated, so that instantaneous or

simultaneous operation of both control valves is required to operate the master valve; and further so that the pressure is released, permitting the master valve to close after a pre-determined time period when both manual valves are operated simultaneously, unless locking means hereinafter set forth are employed. The valve arrangement is such that the absence of locking means repeated operation is prevented upon one simultaneous operation of the manual valves.

21 designates the master control valve, this including a casing 22 having a self-closing, normally-closed, intake valve head 23 therein, a pressure chamber 24 having a piston 25 therein connected by a stem 26 to the intake valve head 23, so that the two act as a unit. The casing is also, in this embodiment of the invention, provided with a second pressure chamber 27 therein, in which works a piston 28 connected by a stem 29 to the piston 25. The control valve 21 is also provided with a port 30 which communicates with a conduit 31 leading to the intake end of the cylinder 8 and controlled by the intake valve head 23. The intake valve head 23 is acted upon by a returning spring 32 to close the same. The portion of the casing 22 of the master valve, which is controlled by the valve head 23, is connected by a pipe 33 to the main line 34 of a pressure supply pipe which is connected to a suitable source of compressed air. 35 and 36 designate respectively the manually operable two hand control valves, each of which includes a casing 37, a combined intake and exhaust valve therein including an intake head 38, a normally-open exhaust head 39 connected by a stem 40 so that they act in unison, the unit being normally held with the intake closed and the exhaust open by the spring 41. The exhaust valve head is shown as formed with a stem 42 extending outside of the valve casing, where it coacts with a manual 43. When only one valve 35 or 36 is opened, the air will flow out past the open exhaust head of the other valve through port 38a.

The manuals shown in Figures 1 and 4 are depressible plates normally flush with the surface of the table 4, they being here shown as hinged at 44 and depressible against the action of returning springs 45. When depressed, they strike the stems 42 and operate the control valves 35, 36 against the action of the returning springs 41.

46 designates a pressure tank connected in the main supply line 34 in multiple with the pipe 33 and also connected preferably in multiple with the valve casings of the manual valves 35, 36 through pipes 48, 49.

50 designates a throttle valve located in the pipe 47 connecting the tank 46 to the main intake 34, this valve serving to time the building up of pressure in the tank sufficient to operate the master control valve, when both manuals are operated. It is adjustable to vary the time element. It includes a needle 51 adjustable axially into and out of the passage of the valve. A suitable gage 52 is connected to the tank to indicate the pressure thereof. This is exposed on the front edge of the table. D is a valve-controlled drain pipe for the tank. Also, the tank and throttle valves are preferably enclosed within a suitable housing 53. The casings 37 of the manually operable valve 35, 36 have outlet ports communicating with a pipe 54 which communicates with the pressure chamber 24 of the master valve 21. When the valves 35, 36 are operated simultaneously by depressing the manuals 43, the in-

take valve heads 38 thereof are opened against the action of the springs 41 and the exhaust valve heads 39 closed, so that air passes from the tank 46 through the pipes 48, 49 to the intake 5 ends of the valve casings 37 past the open intake valve heads and out through the pipe 54 to the pressure chamber 24 of the master control valve 21, thus actuating the piston 25 to open the valve head 23, so that air will pass from the main line 10 34 through the pipe 43 to the valve casing of the master valve, past the open intake valve head 23 out through the port 30 and conduit 31 to the cylinder 8 and actuate the piston 10 on its power stroke to close the machine. If but one manual 15 valve 37 is operated, the pressure passing through the pipe 54 is insufficient to operate the piston 25 in the master control and also passes out through the exhaust port 38a of the other valve.

The disabling or bleeder means consists of a 20 bleeder passage 55 through the partition between the pressure chambers 24 and 27 of the master control valve, this passage having an adjustable needle valve 56 therein. The throttle valve 51 is similar in construction to the valve 56.

The chamber 27 of the master control is formed with exhaust passages 57 which open to the outer air. Thus, when but one manually operated valve 37 is opened, the pressure fluid bleeds out through the passage 55 and to the outer air through the passage 57 and also out through the exhaust passage 38a of the other manually operated valve, so that if the control valves 35, 36 are operated alternately and not simultaneously, there will not be sufficient pressure in the chamber 30 34 of the master valve to actuate the piston 25. The press is opened by releasing the pressure fluid in the cylinder 8 through the master control valve, as will be hereinafter described.

The purpose of the bleeder passage 55 is to prevent sufficient pressure building up in the chamber 24 of the master valve to actuate the piston 25, and hence open the master valve 23, when one of the manual valves 37 is held operated by one hand and the other is in normal position, and subsequently the operator inadvertently operates the other valve, as by inadvertently leaning against the manual thereof, so that pressure gradually builds up in the tank through the valve 50 to a point where sufficient pressure would otherwise build up in the chamber 24 of the master valve to actuate the piston 25. This operation is possible and has occurred, although it is not a common occurrence, for the operator to operate one manual valve 35 or 36 with one hand and to continue in laying the garment on the pressing element 2 with the other hand, and while so doing, move her body around so as to inadvertently operate the other manual valve. The inadvertent operation causes the pressure to build up to operating pressure in the tank 46 through the valve 50, and hence the press closes while the operator is still arranging the lay with one hand. By reason of the bleeder 55, the pressure fluid entering the chamber 24 bleeds out through the passage 55 as fast as it feeds into the tank 46 through the valve 50.

In a pressing machine, such as a garment or laundry press, the machine remains closed and is opened at the will of the operator by operating the release valve or the release valve may be automatically opened by a timer after a pre-determined period. In the machine here shown, the machine is opened by operating manually operated release valve which releases locking means for holding the master valve in its op-

erated position. The means here shown consists of a connection operated by the closing movement of the press. This connection is here shown as a pipe 59 leading from a port 60 in the side of the cylinder 8 to the chamber 27 of the master control valve in which the piston 28 works. After the intake valve head 23 has been opened by the operation of the two hand control valves and the piston 10 passes the port 68, air under pressure from the cylinder passes from the pipe 59 to the chamber 27 of the master valve on the pressure side thereof and thus holds the intake valve head 23 in its open position. The valve head 23 is returned to its normal closed position upon the operation of a release valve previously referred to, which operates to exhaust the air from the pressure side of the chamber 27 of the master valve.

62 designates the release valve, this including a casing 63 and a self-closing, normally-closed exhaust valve 64 therein, it being closed by a spring 65. The end of the stem of the valve is arranged to be depressed by a manual 66 similar to the manuals 43. The valve casing 63 is connected to the chamber 27 by a pipe 67. Upon the opening of the release valve, air will be exhausted from the pressure side of the piston 28 through the pipe 67, valve casing 63 and out through the exhaust passage 68, so that the spring 62 is free to return the intake valve head 23 of the master control to its normal closed position. The casing of the master control is also formed with suitable outlets 69 which with the passage 51 prevent the pistons 25, 28 from becoming air-bound.

In Figure 2, the master control valve is shown in detail, and the piston 25 is a unit with a valve seat 23^a connected to the normally-closed intake valve head 23. The head 23^a is a normally open exhaust valve. The heads 23, 23^a constitute a two-way or a combined intake and exhaust valve. The exhaust valve head 23^a seats on the valve seat 71 when it has been operated by the two hand control operation to open the intake valve head 23, so that when this intake valve head 23 is open, the air pressure can not pass into the chamber 24, and when the release valve is operated, the air can exhaust from the cylinder 8 through the pipe 31 into the chamber 24 and out through the passages 69 and also the air bleeding through the passage 55 into the chamber 27 can bleed out through the passage 57 instead of being trapped. These exhaust passages 69, 72, 73 open into a passage which constitutes muffler 72, 73 of any suitable construction.

In a machine where the head or movable part has a continuous closing and opening movement, or does not remain closed, or where the opening movement follows immediately the closing movement, the automatic locking means controlled by the movement of the machine may be omitted, in which case, owing to the pressure tank 46 and the two hand control system, repeated operations of the press can not take place upon one operation of both manuals, because of the predetermined time element required to build up sufficient pressure in the tank 46 to effect the operation of the master control when both manuals are operated.

In Figure 8 is shown a construction by which the pressure in the tank required to operate the master control valve when two manuals are operated simultaneously may be built up quickly for fast successive but simultaneous operation of the pair of manuals. This feature consists of a normally-closed valve in the pipe line from

the main supply to the tank and around the throttle valve 50. 14 designates the valve casing having a normally-closed intake valve 78 therein, the casing being connected on the inlet side of the valve head 75 to the main line 34 by a conduit 76 and from the opposite side of the valve head 75 to the tank 46 by a pipe 11. The valve head 75 is closed and normally held closed by a spring 78. It is opened by a pressure operated motor consisting of a diaphragm chamber 79 having a diaphragm 80 therein pressing against the head of a plunger 81 which thrusts against a second web or diaphragm 82 which in turn thrusts against the head 83 on the stem 84 of the valve head 75. The space between the two diaphragms is vented to the outer air through passages 85. The pressure side of the diaphragm chamber 79 is connected by a pipe 86 to the pipe 54 from the two hand control valves 35, 36. When both two hand controls are operated, the pressure fluid enters the diaphragm chamber at the same time it enters the chamber 24 of the master control valve and actuates the diaphragm 80 therein to open the intake valve 75 to permit air to pass unthrottled from the main line 34 to the tank 46 around the throttle valve 50.

The spring 78 is of sufficient strength to hold the valve 75 closed against opening by the diaphragm 80 under the air pressure that would be passed by the operation of one manual only. The operation of both manuals is required to conduct sufficient pressure against the diaphragm 80 to overcome the spring 78.

The construction shown in Figure 8 is provided with release means similar to that shown in Figure 4, but the locking and the release means may be omitted. One way of dispensing with them is by locating a cut off valve 87 in the pipe 59 leading from the port in the side of the cylinder to the pressure side of the piston 28 in the chamber 27 of the master control. In Figure 8, the manuals for operating the valves are shown as slightly different from those shown in Figure 4. In Figure 8, instead of being depressible plates or panels in the table, they are elongated strips or plungers 88 sliding in slots formed in the table against the action of returning springs 89.

In Figure 7, the master control valve head is shown as operated by diaphragms instead of cylinders and pistons, and the bleeder or disabling means located to bleed the air from between two diaphragms. 210 designates the master control valve; 90 the casing thereof; 91 the intake valve head corresponding to the head 23 (Figure 4); 92 the spring for closing the valve 91; 93 the main line intake pipe; and 94 the outlet to the cylinder 8. 95 designates a plunger connected by a stem 96 to the valve head 91, so that they act as a unit. This plunger, when operated, seats against a seat 71^a. 97 is a pipe connected to the two hand control and corresponding to the pipe 54 (Figure 4). 98 is a diaphragm located in the diaphragm chamber at one end of the casing 95, the diaphragm thrusting against the head on the plunger 95. 99 is the second diaphragm spaced from the diaphragm 98 and separating the casing into two chambers 100 and 101 located respectively between the diaphragms and at one side of the diaphragm 99. The pipe 97 communicates with the chamber 100 through a disabling or needle valve 102 corresponding to the disabling or needle valve 55 (Figure 4). The chamber 101 is connected to a pipe 103 corresponding to the pipe 59 (Figure 4) leading from the port in the

side of the cylinder 8. In operation, when both the two hand controls are operated simultaneously sufficient air pressure passes through the pipe 97 past the disabling valve into the chamber 100 between the diaphragms to actuate the plungers 98, and hence, open the intake valve head 91 to the intake of air from the main line, so that air passes past the valve head 91 and out through the pipe 94 to the cylinder 8 to actuate the piston therein. When the piston passes the port in the side of the cylinder, air passes through the pipe 103 from the diaphragm chamber 101 actuating the diaphragm 99 therein to follow up the diaphragm 98 and hold the plunger 98 in its operated position, and hence hold the valve head 91 open to the inlet of air from the main line to the cylinder 8. Upon the operation of the release manual, the air is exhausted from the diaphragm chamber 101, the same as it is exhausted from the chamber 27 in the construction shown in Figure 4. When the air is thus exhausted from the diaphragm chamber 101, the intake valve head 91 closes under the impetus of the spring 92. Also, the plunger 98 is moved into the position shown in Figure 7, so that the air can exhaust from the cylinder back through the pipe 94 past the valve seat 96 into the plunger chamber 95 and out through the exhaust passage 104.

In Figures 5 and 6, the cylinders and pistons for opening the master control valve and locking it closed are shown as arranged parallel with the master control valve instead of in alignment therewith, as in Figures 2 and 7.

In Figures 5 and 6, 105 designates a body in which the valve head 106, corresponding to the valve head 23, operates, this having a stem 107 connected to the intake valve 23 of the master control (Figure 2) and coacting with the seat on the body 30 (Figure 2), the same as the valve 23a coacts with its seat. The valve 106 is provided with a stem 108 extending outside of the body 105. 109 and 110 are cylinders mounted parallel to each other at one side or above the body 105 and supported thereon, as by a bracket 111, pistons corresponding to the pistons 25 and 28 operating in the cylinders 109 and 110, respectively, the rods 112 and 113 of these pistons extending to the outside of the cylinders, the cylinder 109 being connected to a pipe corresponding to the pipe 54 (Figure 4) which conducts the pressure from the manual control valves and the cylinder 110 being connected to a port in the side of the power cylinder 8 by a pipe corresponding to the pipe 59 (Figure 4). The motion of the pistons 112 and 113 is transferred to the rod 108 through a Y-shaped lever 114 having a hub or mounted on a pivot 115 extending through ears 116 on the bracket 111. The arms of the Y formation coact respectively with the ends of the piston rods 112, 113 and the leg of the Y formation coacts with the end of the valve rod 108. The body 105 is provided with exhaust passages constituting a muffler 117 corresponding to the muffler 69 and of the same general construction, the muffler having outlet perforations 118 opening into the outer air. In operation, when the manuals are simultaneously operated, air enters the cylinder 109, actuates the piston and its rod 112, rocking the lever 114 causing the leg of the Y formation to thrust on the end of the rod 108 and move the valve 106 on its seat corresponding to the seat 71a (Figure 2) and through the stem 107 open the intake 23 of the master control, so that air passes by the intake 23 through the passage of the body 30 into the power cylinder 8. When the piston 11

in the power cylinder 8 passes the port 60, air passes through the pipe 59 to the cylinder 110, actuates the piston therein to bring the end of its rod 113 against the other arm of the Y formation of the lever 114 and thus hold the lever 114, and hence the valve 106 and the intake valve 23 of the master control in the position into which it has been operated by the piston in the cylinder 8, upon the proper operation of the manually operated valves 35, 36. The cylinder 110 is also connected to a release valve, as 82, through a pipe corresponding to the pipe 61, so that upon operation of the release valve, the air from the cylinder 110 is exhausted, permitting the intake valve 23 to close and the valve 106 to open, and hence the air exhaust from the power cylinder 8 out through the muffler 117 in a manner similar to the construction shown in Figure 2.

In all constructions, there is only sufficient air in the pressure tank 46 to effect the operation of the piston 25 or the diaphragm 98 or the piston in the cylinder 109 upon the simultaneous operation of both manually operated valves 35, 36 and the operation of one valve ahead of the other results in the lowering of the pressure in the tank 46 to such an extent that there is not sufficient pressure to operate the master control valve upon alternate operation of the manually operated valves. Also, upon the proper simultaneous operation of the two hand control valves 35, 36, the pressure although sufficient to operate the master control valve immediately bleeds out through the passage 53, so that the operator must hold both valves depressed for a predetermined period. This period in the machine here illustrated is long enough for the head 1 to come down close to the buck 2 or long enough for the piston 10 to uncover the port 60, which controls the flow of air through the locking cylinder 21 or the diaphragm chamber 101 (Figure 7) or the cylinder 110 (Figures 5 and 6).

In machines in which the opening and closing movement is continuous without the machine remaining closed and in which means for locking the machine closed is dispensed with, the bleeding of the air through the bleeder valve 55 prevents successive operations upon one simultaneous operation of both manually operated valves 35, 36. In machines with such an operation, it may be necessary to build up the pressure in the tank 46 faster than in machines which are held closed for a period of time, instead of being instantly opened. In such machines, the tank 46 may be built up to the required pressure in a shorter time by eliminating the throttle valve 60 or shunting around the throttle valve 60, as seen in Figure 8, by means of the pipe 71. The time element in filling the tank 46 to the required pressure is sufficient to require the repeated operations of the manually operated valves 35, 36.

What I claim is:

1. A two hand control for power actuated machines having a pressure operated motor, including a self-closing, normally-closed master valve for controlling the flow of working fluid to the motor and pressure operated means for operating it, a main working fluid supply line connected to said master valve and normally closed thereby, manually-operable, self-returnable control valves of the combined intake and exhaust type normally arranged with their intakes closed and exhausts open, a tank connected in the main line, and a throttle valve located to time the flow of pressure fluid from the main line to the tank, and the building up of pressure in the tank to a

predetermined pressure, the tank being connected in multiple with the control valves and the control valves being connected in multiple with the pressure operated means of the master valve, the tank being of sufficient capacity only to supply pressure to the pressure operated means of the master valve for one opening operation only of the master valve, all whereby upon operating only of one control valve, the pressure fluid exhausts through the other control valve, and the pressure of the tank drops below a predetermined and sufficient pressure to operate the pressure operated means of the master valve and the operation of both control valves substantially in unison is required to operate the master valve, and bleeder means for gradually releasing the pressure in the pressure operated means of the master valve.

2. A two hand control for power actuated machines having a pressure operated motor including a self-closing, normally-closed, master valve for controlling the flow of working fluid to the motor and pressure operated means for opening it, a main working fluid supply line connected to said master valve and normally closed thereby, a pair of manually operable control valves each having an inlet port, an exhaust port, and an outlet port, said valves normally arranged with their inlet ports closed and their outlet ports communicating to atmosphere through said exhaust ports and operable to open their inlet ports in communication with the outlet ports and to close their exhaust ports, a tank connected in the main line through a throttle valve arranged to time the flow of fluid from the main line to said tank and the building up of main line pressure in the tank, the inlet port of each valve being connected to the tank and the outlet ports of said valves being connected in multiple with the pressure operated means of the master valve, the tank being of sufficient capacity to supply fluid to the pressure operated means of the master valve sufficient only for one opening operation of the master valve, all whereby upon operating only one of the control valves the working fluid exhausts from the tank through the other control valve leaving an insufficient supply of said fluid to operate the pressure operated means of the master valve upon subsequent operation of said other control valve, and the operation of both control valves substantially simultaneously is required to operate the master valve, and bleeder means for gradually releasing the pressure in the pressure operated means of the master valve, said bleeder means being adjusted to permit a flow of fluid at least equal to the flow of fluid through said throttle valve.

3. A two hand control for power actuated machines having a pressure operated motor including a self-closing, normally-closed, master valve for controlling the flow of working fluid to the motor and pressure operating means for opening it, a main working fluid supply line connected to the pressure operated motor through said master valve and normally closed thereby, a plurality of manually operable, self-returnable control valves, the inlet ports of said valves being connected in multiple to said supply line, and the outlet ports of said valves being connected in multiple to the pressure operated means of the master valve, bleeder means operable to gradually release the pressure in the pressure operated means of the master valve, said control valves, when operated substantially simultaneously, permitting sufficient

fluid to flow to said pressure operated means to effect opening of the master valve, and said bleeder means being operable to bleed off sufficient fluid upon the operation of any one of said control valves to prevent sufficient operating pressure in said operating means of the master valve.

5. A two hand control for power actuated machines having a pressure operated motor including a self-closing, normally-closed, master valve for controlling the flow of working fluid to the motor and pressure operating means for opening it, a main working fluid supply line connected to the pressure operated motor through said master valve and normally closed thereby, a plurality of manually operable, self-returnable control valves, the inlet ports of said valves being connected in multiple to said supply line, and the outlet ports of said valves being connected in multiple to the pressure operated means of the master valve, bleeder means operable to gradually release the pressure in the pressure operated means of the master valve, said control valves, when operated substantially simultaneously, permitting sufficient fluid to flow to said pressure operated means to effect opening of the master valve, and said bleeder means being operable to bleed off sufficient fluid upon the operation of any one of said control valves to prevent sufficient operating pressure in said operating means of the master valve, and means operable upon such simultaneous operation of said control valves to instantly replenish the supply of fluid in the tank for a successive operation.

35. A two hand control for power actuated machines having a pressure operated motor including a self-closing, normally-closed, master valve for controlling the flow of working fluid to the motor and pressure operated means for opening it, a main working fluid supply line connected to said master valve and normally closed thereby, a pair of manually operable control valves each having an inlet port, an exhaust port, and an outlet port, said valves normally arranged with their inlet ports closed and their outlet ports communicating to atmosphere through said exhaust ports and operable to open their inlet ports in communication with the outlet ports and to close their exhaust ports, a tank connected in the main line through a throttle valve arranged to time the flow of fluid from the main line to said tank and the building up of main line pressure in the tank, said tank being also connected in the main line through a normally closed replenishing valve operable, when open, to instantly replenish the valve in said tank and operating means for opening it, the inlet port of each valve being connected to the tank and the outlet ports of said valves being connected in multiple with the pressure operated means of the master valve and with the operating means of said replenishing valve, the tank being of sufficient capacity to supply fluid to the pressure operated means of the master valve sufficient only for one opening operation of the master valve, all whereby upon operating only one of the control valves the working fluid exhausts from the tank through the other control valve leaving an insufficient supply of said fluid to operate the pressure operated means of the master valve upon subsequent operation of said other control valve, and the operation of both control valves substantially simultaneously is required to operate the master valve.

ERNEST DAVIS.
